E. MILLER

INTERLOCK FOR SAFETY SWITCHES

Filed April 18, 1921

Fig. 1.

UNITED STATES PATENT OFFICE.

ERNEST MILLER, OF LOS ANGELES, CALIFORNIA.

INTERLOCK FOR SAFETY SWITCHES.

Application filed April 18, 1921. Serial No. 462,235.

To all whom it may concern:

Be it known that I, ERNEST MILLER, a citizen of the United States, residing at Los Angeles, in the county of Los Angeles and 5 State of California, have invented a new and useful Interlock for Safety Switches, of which the following is a specification.

My invention relates to electric switches such as are commonly used as service 10 switches between the line of the electric power producer and the premises of the individual consumers.

My invention has a peculiar utility when used at the entrance to buildings and while 15 readily adaptable for other purposes, the following description will be restricted in a measure to this particular use. It is necessary wherever a power company's lines enter a building to provide a switch by which 20 the service to that building may be entirely disconnected. It has been the practice for many years to supply open type knife switches for this purpose. These switches are extremely dangerous both as fire and life 25 hazards as they have exposed live parts which a person may come in contact with and which may be short-circuited by accidental contact with metal members.

The power companies are attempting to 30 replace these open switches with enclosed switches, that is to say, with switches which are entirely inside a metal box having a hinged cover. By enclosing the switches in a metal box, the danger of accidental contact is considerably reduced. It is still, however, possible where the ordinary knife 35 switch is simply placed in a cabinet for accidents to happen especially as the consumer may leave the box open and it has become 40 the practice to provide an operating handle on the outside of the box so that the switch can be opened and closed without danger of the operator coming in contact with any live part of the switch, and so that it is not necessary 45 for him to open the box in the ordinary operation of the switch.

It is, however, common practice to place fuses inside the box and the box must be 50 opened for renewal of these fuses in case they are blown. Safety boxes are, therefore, manufactured in which the fuses are placed on the dead side of the switch and in which the cover is interlocked with the switch in such a manner that the switch must be 55 opened before the cover is opened, thus in-

suring that practically all of the live parts of the switch shall be dead before the cover is opened and in which the switch is interlocked with the cover so that it cannot be closed until after the cover is closed, thus 60 preventing the cover being left open with the switch and fuses alive.

It is an object of my invention to provide a novel form of interlock for accomplishing 65 this result.

Further objects and advantages will be made evident hereinafter.

In the drawing which is for illustrative purposes only,

Fig. 1 is a cross section through a switch 70 box embodying my invention.

Fig. 2 is a side view showing the handle.

Fig. 3 is a plan view of the interlock mechanism proper.

Fig. 4 is an end view of the box.

Fig. 5 is a view of how the mechanism disengages the door latch.

Fig. 6 is a view showing the mechanism latch engaged due to the opening of the door, and,

Fig. 7 is a view showing the mechanism latch disengaged due to the closing of the door.

In this drawing, 11 is the box, 12 is the cover and 13 is the hinge for the cover. 85 The switch is mounted on an insulating base 20, and consists of fuse clips 21, enclosed fuses 22, hinge jaws 23, break jaws 24 and blades 25. The blades are pivoted at 26 in the hinge jaws 23 and carry a cross bar 27 90 on their free ends. Secured to the cross bar 27 is a bracket 28 to which a link 29 is pivoted by a pin 30. The link 29 has a slot 31 at one end through which an operating rod 32 passes. This operating rod 32 passes 95 through the side of the box 11 as shown in Fig. 4, and is bent up and over the switch passing through the hub 35 of the handle 36 being outside of the box. The handle 36 and the journal end 37 of the member 32 100 turn about a center 38 indicated in Fig. 1 which is above and outside of the pivot 26 of the switch. A tension spring 39 is secured to an eye 40 on the link 29 and to the operating member 32. Mounted on a pivot 40 105 on the side of the switch is a sheet metal member 41 forming a cover latch 42 and a mechanism latch 43. The cover latch 42 may engage a hook 44 carried on the cover 12, and a tension spring 45 is provided which 110

tends to draw the latch 42 into engagement with the hook 44 and which also tends to draw the latch 43 into engagement with the operating bar 32 when the switch is open. 5 This will be better understood from a description of the method of operation which is as follows:

The switch being closed or in the position shown in full lines in Fig. 1 and the cover 10 being closed with the member 41 in the position shown in full lines in that figure, it is evident that the cover is locked by the hook 42. The cover being locked, it cannot be opened so long as the switch is closed. For 15 the purpose of opening the switch, the operator grasps the handle 37 and moves it from the position shown in full lines in Fig. 2 to the position shown in dotted lines in that figure. During the initial portion of this 20 movement, the member 32 slides in the slot 31 exerting a tension on the spring 39. As soon as the member 32 reaches the end of its movement in the slot 31, it starts to positively pull upon the cross bar 27 until the 25 friction of the break jaws 24 on the blades 25 is insufficient to resist the tension of the spring 39 at which time the blade is pulled out of contact with the joint 34 by the spring 39, thus providing a quick break and eliminating 30 the tendency to arc between the jaws 24 and the blades 25. The shape of the hook 43 is such that it is pushed down into the position shown in dotted lines in Fig. 1 by the operating rod 32 when the switch is entirely 35 open, thus releasing the latch 44. The cover can now be opened. The blades 25, the hinge joints 23, the fuse clips 21 and the switch 22 are disconnected from the circuit and dead. The break jaws 24 are 40 still, however, alive but are fairly well shielded by the remaining mechanism of the switch. The fuses 22 can be inspected or replaced without serious danger of accident. If, however, the user attempts to close the 45 switch, the spring 45 causes the latch 43 to follow up and engage the member 32 as soon as this member starts to move towards its closing position, the latch 43 thus catching and holding the rod 32 and preventing 50 the switch from being closed while the cover is open. If, however, the cover is closed, the hook 44 pushes the latch 42 back far enough to release the latch 43 and the switch may be closed.

55 I claim as my invention:

1. In a safety switch having a case, a cover for said case, and a mechanism inside said case, the combination of a cylindrical pivot; a member having a cylindrical hole fitting 60 on said pivot; a cover latch formed on said member; a mechanism latch formed on said member; a spring tending to throw each of said latches into engagement; means by which the mechanism when open throws the 65 cover latch out of engagement with said mechanism.

cover; and means by which the cover when closed throws the mechanism latch out of engagement with said mechanism.

2. In a safety latch having a casing, a 70 cover for said case, and a mechanism inside said case, the combination of a cylindrical pivot; a member having a cylindrical hole fitting on said pivot; a cover latch formed on said member; a mechanism latch formed on said member; a spring tending to throw 75 each of said latches into engagement; an arm on said mechanism pressing against said member and throwing said cover latch out of engagement with said cover when said mechanism is in the open position; and means by which the cover when closed throws the mechanism latch out of engagement with said mechanism.

3. In a safety latch having a casing, a 80 cover for said case, and a mechanism inside said case, the combination of a cylindrical pivot; a member having a cylindrical hole fitting on said pivot; a cover latch formed on said member; a mechanism latch formed on said member; a spring tending to throw 85 each of said latches into engagement; means by which the mechanism when open throws the cover latch out of engagement with said cover; and a hook carried by said cover and so shaped that it throws said mechanism latch out of engagement with said mechanism when said cover is closed.

4. In a safety switch having a case, a cover for said case, and a mechanism inside said case, the combination of a cylindrical pivot; a member having a cylindrical hole fitting on said pivot; a cover latch formed on said member; a mechanism latch formed on said member; a spring tending to throw 100 each of said latches into engagement; an arm on said mechanism pressing against said member and throwing said cover latch out of engagement with said cover when said mechanism is in the open position and a hook carried by said cover and so shaped 105 that it throws said mechanism latch out of engagement with said mechanism when said cover is closed.

5. In a safety switch having a case, a cover for said case, and a mechanism inside 110 said case, the combination of a cylindrical pivot; a member having a cylindrical hole fitting on said pivot; a cover latch formed on said member; a mechanism latch formed on said member; a tension 115 spring having one end secured to said case and the other secured to member in such a manner as to tend to force said cover latch and said mechanism latch into engagement; means by which the mechanism when open throws the cover latch out of engagement with said cover; and means by which the cover when closed throws the mechanism latch out of engagement with said mechanism.

6. In a safety latch having a casing, a cover for said case, and a mechanism inside said case, the combination of a cylindrical pivot; a member having a cylindrical hole fitting on said pivot; a cover latch formed on said member; a mechanism latch formed on said member; a tension spring having one end secured to said case and the other secured to member in such a manner as to tend 10 to force said cover latch and said mechanism latch into engagement; an arm on said mechanism pressing against said member and throwing said cover latch out of engagement with said cover when said mechanism 15 is in the open position; and means by which the cover when closed throws the mechanism latch out of engagement with said mechanism.
7. In a safety latch having a casing, a cover for said case, and a mechanism inside said case, the combination of a cylindrical pivot; a member having a cylindrical hole fitting on said pivot; a cover latch formed on said member; a mechanism latch formed 20 on said member; a tension spring having one end secured to said case and the other secured to member in such a manner as to tend to force said cover latch and said mechanism latch into engagement; an arm on said mechanism pressing against said member and throwing said cover latch out of engagement with said cover when said mechanism 25 is in the open position; and a hook carried by said cover and so shaped that it throws said mechanism latch out of engagement with said mechanism when said cover is closed.
8. In a safety switch having a case, a cover for said case, and a mechanism inside said case, the combination of a cylindrical pivot; a member having a cylindrical hole fitting on said pivot; a cover latch formed 30 on said member; a mechanism latch formed on said member; a tension spring having one end secured to said case and the other secured to member in such a manner as to tend to force said cover latch and said mechanism latch into engagement; an arm on said mechanism pressing against said member 35 and throwing said cover latch out of engagement with said cover when said mechanism is in the open position; and a hook carried by said cover and so shaped that it throws said mechanism latch out of engagement with said mechanism when said cover is closed.

In testimony whereof, I have hereunto set 55 my hand at Los Angeles, California, this 9th day of March, 1921.

ERNEST MILLER.
